(57) **CLAIM**

The ornamental design for a pump actuator, as shown and described.

DESCRIPTION

FIG. 1 is a perspective view of the pump actuator of our design.

FIG. 2 is a front elevation view thereof.

FIG. 3 is a rear elevation view thereof.

FIG. 4 is a left side elevation view thereof, the right side elevation view being a mirror image thereof.

FIG. 5 is a top plan view thereof; and,

FIG. 6 is a bottom plan view thereof.

The broken line showing of a stem depending from the lower surface of the pump actuator is for illustrative purposes only and forms no part of the claimed design.
